UNITED STATES PATENT OFFICE.

DAVID ZAKIM, OF NEW YORK, N. Y., ASSIGNOR TO STERLING METAL NOVELTY M'F'G CO., INC., OF NEW YORK, N. Y., A CORPORATION OF NEW YORK.

LEAD PENCIL.

Application filed March 13, 1922. Serial No. 543,133.

To all whom it may concern:

Be it known that I, DAVID ZAKIM, a citizen of Poland, and a resident of New York, in the county of Bronx and State of New York, have invented certain new and useful Improvements in Lead Pencils, of which the following is a specification.

The invention relates to improvements in mechanical lead pencils of the propeller type, and resides in the novel features of construction and relative arrangement of parts hereinafter described and claimed.

The pencil of my invention comprises an exterior tubular barrel or casing tapered at its forward end to form a tip-member, an interior concentric lead-holding and guiding tube whose forward end is tapered to engage the inner tapered walls of said tip-member near the forward end thereof, an ornamental head in which said tube is, at its rear end, secured and which closes the rear end of said exterior casing and has a forward cylindrical plug entering said end and holding said tube, a propeller rod within said tube and having a lug extending through and adapted to travel along a longitudinal slot therein, and a spiral spring or spiral rod within said exterior casing and encompassing said tube and receiving within its convolutions said lug of the propeller rod, said spring having two diameters, the one of smaller diameter extending throughout the main extent of the spring and closely encompassing said tube without binding against the same, and the one of larger diameter being closely coiled and constituting a head which very closely fits within said exterior casing and binds against the same with such force as to render the spring stationary therewith.

One of the novel features of my invention resides in the provision of the aforesaid spiral spring or spiral rod in one part closely encompassing the clutch tube without binding against it and in the other part so tightly engaging the exterior barrel or casing that the spring and casing become so rigidly connected together that the casing cannot rotate on the spring nor the spring within the casing.

A further novel feature of my invention resides in having the tapered forward end of the clutch tube engage the inner walls of the tip-member of the pencil and in providing on the rear end of said tube the head which

carries the tube and closes the outer end of the main casing and is capable of rotary movement therein and thereon for rotating said tube and causing the lug on the propeller rod therein to travel along the convolutions of the spiral spring or rod.

The pencil of my invention also comprises other desirable features which will presently be described, and the object of the invention is to provide a comparatively inexpensive mechanical pencil of improved construction and of increased reliability and efficiency in operation.

The invention will be fully understood from the detailed description hereinafter presented, reference being had to the accompanying drawings, in which:

Fig. 1 is a central longitudinal section, on an enlarged scale, through a pencil embodying my invention;

Fig. 2 is a corresponding view of the outer casing of the pencil detached;

Fig. 3 is a side elevation of the interior assembled parts of the pencil shown as withdrawn from the outer casing thereof or ready for insertion into said casing;

Fig. 4 is a detached side elevation of the clutch-tube, and

Fig. 5 is a vertical transverse section through the pencil, taken on the dotted line 5-5 of Fig. 1.

In the drawings 10 designates the exterior tubular casing of the pencil, 11 the interior lead-holding tube, 12 the head carrying said tube and adapted to the outer or rear end of said casing, 13 the propeller rod within said tube and 14 the spiral for cooperation with said propeller rod, said spiral throughout its extent or body portion 15 being of a diameter adapted to closely encompass the tube 11 without binding against the same and at one end being of a larger diameter and closely wound to form a head 16.

The casing 10 is a plain tube shaped at its forward end to form a tapered tip-member 17 whose outer end portion is slit inwardly at opposite sides, as at 9, to form a clutch for engaging the lead.

The tube 11 is concentrically within the casing 10 and tapered at its forward end, as at 18, to form a close fit against the inner tapered walls of the tip member 17, as shown in Fig. 1. The tube 11 is adapted to hold the piece or stick of lead 19, and said tube is formed in its side with a longitudinal

slot 20, which commences at the rear end of the tube and terminates at about the position of the forward end of the spiral 14, said slot being in part interrupted near the 5 head 16 of the spiral by stop lugs 21 formed from the material of the tube and projecting into said slot, as shown more clearly in Fig. 4. The stop lugs 21 are provided to arrest the lug 22 on the propeller rod 13 when said 10 lug and rod have reached the proper limit of their rearward movement.

The head 12 is of ornamental character and has an annular beading 23 to shoulder against the rear end of the casing 10 and an 15 extension or plug section 24 to closely enter and fill the rear end of said casing, said section 24 being of considerable length so as to have a substantial bearing in the casing 10 and be capable of uniformity of rotation 20 within said casing when turned by pressure applied by the thumb and finger to the exposed knob portion of the head 12. The section 24 also has a deep concentric socket 25 which rigidly holds the rear end portion 25 of the tube 11, the slot in said tube permitting said end portion to be expanded and then crowded into said socket so as to effect a rigid connection of the tube with the head 12. The head 12 and tube 11 are 30 rigidly connected together so that rotary motion may be imparted to said tube from said head.

The propeller rod 13 is a plain straight rod adapted at its forward end to engage the 35 rear end of the stick of lead 19, as usual, and having at its rear end a flat lug 22 which projects laterally through and guides in the slot 20 of the tube 11. The lug 22 extends outwardly between the convolutions 40 of the spiral 14 and in length is only slightly less than the space between said convolutions, as shown in Fig. 1. During the operation of the rod 13, said rod may be moved forwardly until the lug 22 be- 45 comes arrested at the forward end of the slot 20 and may be moved rearwardly until said lug becomes arrested by the stop lugs 21, which are so placed as to prevent the lug 22, in regular operation, from leaving the 50 regularly formed convolutions of the body portion 15 of the spiral 14. The forward end of the slot 20 in the tube 11 is so positioned with relation to the spiral 14 that the lug 22 becomes arrested thereat while 55 said lug is still confined by the spiral, said lug thus being prevented from escaping from the forward end of the spiral.

The spiral 14 is formed by coiling a rod 60 of wire to form the body portion 15 and head 16 thereof, said portion 15 snugly, though freely, encompassing the tube 11, and the head 16 being of increased diameter and formed of close side-by-side convolu- 65 tions of the rod of wire and very tightly fitting the rear end of the exterior casing

10 so as to become bound thereto. The head 16 is of adequate length to obtain a reasonably long bearing against the interior of the casing 10 and is independent of the head 12, whose plug-section 24 reaches the 70 rear end of said head 16. The spiral 14 remains rigid with the casing 10 during the rotary movement of the head 12 and tube 11, and to accomplish this result is the reason for the head 16. 75

In practice the interior parts of the pencil will be assembled in the manner shown in Fig. 3, less the lead 19, and inserted into the casing 10 from the rear end thereof, all of the parts with reasonable freedom entering the casing 10 with the exception of the head 16 which requires a limited amount of pressure to force it into the casing 10, since said head is meant to tightly bind against said casing and position the body 80 of the spiral therewith. The pressure required for forcing the head 16 into the casing 10 may be conveniently applied to the head 12 whose plug-section 24 when moved into the rear end of the casing 10 will force 85 said head 16 in advance of it to position within said casing. After the parts of the pencil have been assembled, the lead 19 may be introduced thereto in the usual well understood manner, the propeller rod 13 being moved forwardly against the lead to project it and rearwardly to allow the lead to be pushed back into the pencil, and said rod being operated by rotating the head 12 and tube 11 in one direction or the other, as 90 may be required, to carry the lug 22 on said rod along the convolutions of the body portion 15 of the stationary spiral 14. 95

One important feature of my lead pencil resides in the fact that the forward or tip end of the casing 10 is slit at 9 to create a clutch for holding the lead during the use of the pencil in writing. The tube 11 not being slit at its forward end is not a clutch tube. I have found that variations in the 100 sticks of lead 19 result in breakage at the writing point of the lead when the tube 11 is made to constitute the clutch, and I have also found that when the clutch feature is transferred from the tube 11 to the forward 105 end of the tip-member 17, as I have shown, the leads are very much less liable to breakage at the point and that the pencil as a whole is better adapted to accommodate 110 itself to the irregularities of the leads 19. 115

The lug 22 is so proportioned with respect to the inner diameter of the head 16 that I may screw the tube 11 inwardly into the spiral 14 until said lug reaches its proper position within the body-portion 15 of the 120 spiral. Thereafter the tube 11 carrying the spiral, as shown in Fig. 3, may be pushed into the casing 10. If preferred the spiral 14 may be introduced into the casing 10 before the tube 11 is applied to position. After 125 130

the tube 11 and spiral 14 are in position within the casing 10 I may lock the tube 11 and casing 10 together by means of an annular groove 8 formed in the head 24 and a depression 9 formed on the casing by driving a small portion thereof inwardly into said groove. The groove 8 and the depression or lug 9 entered therein, will permit the head 12 and tube 11 to be rotated in either direction, but said groove and depression will prevent the tube 11 from being withdrawn outwardly from the casing. The parts are of such durable construction that it will not be necessary to withdraw the tube 11 from the casing 10, since the leads 19 may always be introduced to said tube 11 from the tip-end of the casing 10. The structure is entirely operative without the groove 8 and depression 9, and said features are only provided when it is desired that the interior parts of the pencil shall not be withdrawn from the casing 10.

It will be seen that my pencil is composed of a few durable parts which may be easily assembled and which when assembled provide a pencil which is efficient in use and not liable to become out of order or require special attention.

What I claim as my invention and desire to secure by Letters-Patent, is—

1. A lead pencil comprising an exterior tubular casing having a forward tip-member, a rotary head at the rear end of said casing, a lead-holding tube secured to said head and longitudinally slotted in one side, a propeller rod within said tube having a laterally extending lug to guide in said slot thereof, and a spiral encompassing said tube and receiving between its convolutions the outer end of said lug, said spiral having a body portion of uniform diameter along which said lug has its traveling movement and a head portion of larger diameter

tightly fitting said casing and stationary therewith.

2. A lead pencil comprising an exterior tubular casing having a forward tip-member, a rotary head at the rear end of said casing, a lead-holding tube secured to said head and longitudinally slotted in one side, a propeller rod within said tube having a laterally extending lug to guide in said slot thereof, and a spiral encompassing said tube and receiving between its convolutions the outer end of said lug, said spiral having a body portion of uniform diameter along which said lug has its traveling movement and a head portion of larger diameter tightly fitting said casing and holding the spiral stationary therewith.

3. A lead pencil comprising an exterior tubular casing having a forward tip-member, a rotary head at the rear end of said casing, a lead-holding tube secured to said head and longitudinally slotted in one side, a propeller rod within said tube having a laterally extending lug to guide in said slot thereof, and a spiral encompassing said tube and receiving between its convolutions the outer end of said lug, said spiral having a body portion of uniform diameter along which said lug has its traveling movement and at its rear end a closely coiled head of larger diameter tightly fitting said casing and holding the spiral stationary therewith, and said rotary head having an exposed knob portion, a shoulder to engage the end of said casing and a plug-section to engage the head on said spiral and position the same in and close the outer end of said casing.

Signed at New York city, in the county of New York and State of New York, this 2nd day of March, A. D. 1922.

DAVID ZAKIM.
